UNITED STATES PATENT OFFICE.

EUGENE THEIMER, OF NEWARK, NEW JERSEY, ASSIGNEE, BY MESM ASSIGNMENT,
TO BOY F. STEWARD, OF WASHINGTON, DISTRICT OF COLUMBIA.

PROCESS OF ALKYLATING ORGANIC COMPOUNDS.

No Drawing.

Application filed July 29, 1919. Serial No. 314,157.

To all whom it may concern:

Be it known that I, EUGENE THEIMER, a citizen of the United States, residing at Newark, in the county of Essex and State of New Jersey, have invented certain new and useful Improvements in Processes of Alkylating Organic Compounds; and I do hereby declare the following to be a full, clear, and exact description of the invention, such as will enable others skilled in the art to which it appertains to make and use the same.

This invention relates to processes of alkylating organic compounds, more particularly compounds of the paraminophenol type; and it has to do especially with the preparation of methyl phenacetin from phenacetin.

In prior copending applications, Serial Nos. 252,722, filed September 5, 1918, and 301,686, filed June 4, 1919, I have disclosed and claimed novel methods of alkylating compounds having the type formula

30 by the successive action of an alkali metal, such as sodium, and an alkylating agent, such as an alkyl halid. Examples of this class of compounds, to alkylation of which said methods are especially applicable, are phenacetin (acetphenetidin), acetaisidin, formyl anisidin, formyl phenetidin, etc. As 35 stated in said prior applications, during the first stage of the alkylation as ordinarily conducted by prior methods, the mass resulting from the reaction of the alkali metal on the compound to be alkylated tends to congeal even where the reaction is conducted in the presence of a large amount of a suitable solvent liquid such as xylol. This is an undesirable condition and unfavorable for the subsequent treatment with an alkyl halid, especially where the latter is a gas like 40 methyl bromid for example. In order to have the reaction mass in the form of a homogeneous liquid mixture for treatment with the alkylating agent, special measures 45 are taken, in accordance with the inventions

of said prior applications, to attain this result. This can be accomplished, for example, by ensuring the presence, in the reaction mixture resulting from the alkali metal treatment, of a suitable quantity of a later stage product, added prior to the treatment with an alkylating agent. If such addition be made prior to the alkali metal treatment, congealation can be entirely prevented; or if made after congealation has occurred, the congealed mass is thereby liquefied without difficulty.

In general, the objects of the present invention are similar to those of the inventions disclosed in said prior applications, as 50 are also the classes of compounds treated and the resultant products; but the desired results are achieved in a different and, in some respects, a distinctly more advantageous manner, as will hereinafter appear.

55 According to the present process the starting material, that is, the compound to be alkylated, is brought into solution or homogeneous liquid mixture with an inert solvent or vehicle, such as xylol; and this mixture is first subjected to the action of an agent comprising an alkali metal in available form, the free alkali metal itself being suitable, in amount materially less than is required to convert all of said compound 60 into the intermediate alkali metal derivative. Moreover, in alkylating a given quantity of the starting material, it is most desirable not to introduce the entire quantity into the initial mixture, but to use somewhat less, say 65 about two-thirds, for example, with the full proportion of inert solvent or vehicle, the rest of the starting material and of the alkali metal being added at a later stage, as will be explained hereinafter. By proceeding 70 in this manner, all tendency of the intermediate derivative to separate out may be overcome and a homogeneous liquid reaction mixture continuously maintained. While the proportion of alkali metal initially used may vary somewhat, only so 75 much should be used as will yield a non-congealing mixture of said compound with the intermediate derivative and the inert menstruum or vehicle. The resultant liquid 80 mass is then subjected to the action of the desired alkylating agent to convert the intermediate derivative into the desired alkylated compound, which remains after 85 formation in liquid mixture with unchanged 90

95 100 105 110

starting compound and inert menstruum. At this stage there is added more of the starting material, specifically the remainder of the aforesaid given quantity thereof, and 5 also a further amount of alkali metal sufficient to ensure conversion into the alkali metal derivative of any unaltered portion of the starting material initially used, as well as of that added at this stage. 10 Conversion of the resultant intermediate compound into the desired alkylated compound can be effected with the aid of a further quantity of the alkylating agent.

This improved procedure offers certain 15 very important practical advantages. In the first place it enables a very considerably increased output per unit of time with the same apparatus equipment. Furthermore, when the operation is conducted in the manner described above, it is found that complete solution of the theoretically required amount of alkali metal may be effected finally without difficulty; whereas in the methods of said prior applications, the last 20 portions of the alkali metal dissolve only very slowly, making it ordinarily desirable to use somewhat less than the theoretical proportion in order to ensure complete solution. This precaution is rendered unnecessary by 25 the present invention, with the further result that there need be practically no unchanged starting compound to separate from the desired alkylated product. The whole procedure is thus simplified, expedited, and 30 rendered smoother.

In order to afford a fuller understanding of the underlying principles of the invention, a particularly desirable embodiment thereof as applied to the manufacture of methyl 40 phenacetin from phenacetin will be described in detail by way of an illustrative example. Specific quantities of the materials employed will be mentioned, but it will be understood that these may be varied not only 45 in absolute amount but also in proportions, although the proportions hereinafter specified are those which at present are considered best.

In a typical procedure within the invention, where it is desired to convert say 117 50 pounds of phenacetin into methyl phenacetin, only 80 pounds of phenacetin are initially mixed with 100 pounds of warm xylol to give a homogeneous liquid mass. 55 These proportions give a mixture of such density that metallic sodium will float upon it, which is highly desirable. The amount of xylol used is therefore always best limited accordingly. To the warm mixture or solution, contained in a suitable reaction vessel, is added metallic sodium in amount equal 60 in this specific example to about one-half that theoretically necessary for combination with all of the phenacetin present. An 65 addition of about 5 pounds of sodium at

this stage in the present example is good practice. The reaction proceeds vigorously with generation of considerable heat and evolution of hydrogen, the sodium floating on the mixture until completely dissolved, 70 so that the end of the reaction is readily observed. Some of the xylol distils off and may be recovered with the aid of a condenser. The mass resulting from the reaction is a homogeneous liquid which exhibits 75 no tendency toward crystallization and is in ideal condition for the succeeding treatment with methyl bromid. This gas is passed into the liquid mass, to which has desirably been added an amount of xylol sufficient to make 80 up the loss by distillation, until somewhat more has been absorbed than is theoretically necessary to convert the intermediate sodium-phenacetin compound present into methyl phenacetin. Operating with the 85 quantities of materials and under the conditions specified, it is desirable to pass into the mass a volume of gas containing about 21.73 pounds of methyl bromid, whereas theory requires but 20.65 pounds. It is found that 90 the use of the small excess of methyl bromid which the reaction mixture will take up at this stage, about 5 per cent in this instance, has a desirable effect in the remaining stages of the process, particularly in facilitating 95 and expediting complete solution of the second portion of metallic sodium which is now added, after adding the remaining 37 pounds of phenacetin, without its being necessary first to separate the sodium 100 bromid present in the reaction mixture as a result of the treatment with methyl bromid. In the present specific example, this second portion of sodium amounts to ten pounds. As before, the reaction proceeds expeditiously and smoothly to completion, the sodium floating until it has all gone into solution, and moderate external heating being resorted to toward the last if necessary, but the heat of the reaction itself ordinarily 110 sufficing to carry it through. The reaction mass shows no tendency to solidify or crystallize, remaining perfectly liquid throughout. Xylol is best added in sufficient quantity to make up the loss by distillation, as 115 before, and methyl bromid gas is again led into the mass until no longer taken up thereby. A volume of gas equivalent to 40.75 pounds of methyl bromid is sufficient in this instance. The entire amount of phenacetin 120 originally present in the starting batch has now been converted into methyl phenacetin. The xylol solution of methyl phenacetin is next decanted from the accompanying sodium bromid which settles out rapidly under 125 the described conditions of operation, the sodium bromid settling being then thrown on the filter and washed with hot xylol. The xylol is then separated from the methyl phenacetin by distillation at ordinary pres- 130

sure, the distillation being materially expedited in practice by adding a small quantity of water, say a quart or so, to the solution before distilling. The residue of methyl phenacetin may then be purified by vacuum distillation.

It will be understood that the details of operation above described can be varied to a considerable extent without departing from 10 the scope of the invention as defined in the appended claims.

I claim:

1. The process of alkylating acylamine organic compounds capable of alkylation 15 by the action of alkali metal and an alkylating agent, which comprises subjecting an acylamine organic compound in liquid condition to the successive action of an alkali metal in available form and an alkylating 20 agent, in quantity insufficient to bring about congelation of the reaction mass or to effect complete alkylation, and then effecting more complete alkylation by further treatment with alkali metal and alkylating 25 agent.

2. The process of alkylating organic compounds having the type formula

which comprises subjecting such a compound in liquid condition to the action of an alkali metal in available form and in quantity sufficiently less than that molecularly equivalent to said compound to avoid 40 congelation of the reaction mixture, treating the resultant intermediate product in liquid condition with an alkyl halid, and then repeating the treatment with alkali 45 metal and alkyl halid to effect further alkylation.

3. The process of preparing methyl phenacetin which comprises subjecting a liquid mixture of phenacetin and a diluent vehicle 50 to the action of an alkali metal in available form and in amount sufficiently less than that molecularly equivalent to the phenacetin to avoid congelation of the reaction mixture, subjecting the resultant mixture to the action of an alkyl halid, and then effecting further alkylation by successive treatment with more alkali metal and alkyl halid.

4. The process of preparing methyl phe-

nacetin which comprises subjecting a liquid 60 mixture of phenacetin and xylol to the action of about one-half the amount of metallic sodium molecularly equivalent to the phenacetin, passing methyl bromid into the resultant liquid mass, adding to the mass 65 more phenacetin and a further amount of metallic sodium sufficient to react with substantially all the phenacetin present in the mixture, completing the methylation with methyl bromid, and obtaining methyl phenacetin from the mixture finally obtained.

5. The process of preparing methyl phenacetin which comprises subjecting a liquid 70 mixture of phenacetin and a diluent vehicle to the action of an alkali metal in 75 amount sufficiently less than that molecularly equivalent to the phenacetin to avoid congelation of the reaction mixture, subjecting the resultant mixture to the action of an alkyl halid in excess of that theoretically required for complete reaction with all the intermediate alkali compound of phenacetin present, and then effecting further alkylation by successive treatment with 80 more alkali metal and alkyl halid.

6. The process of preparing methyl phenacetin which comprises subjecting a liquid 85 mixture of phenacetin and xylol to the action of about one-half the amount of metallic sodium molecularly equivalent to the 90 phenacetin, passing an excess of methyl bromid into the resultant liquid mass, adding to the mass more phenacetin and a further amount of metallic sodium sufficient to react with substantially all the phenacetin present in the mixture, completing the methylation with methyl bromid, and obtaining methyl phenacetin from the mixture finally obtained.

7. The process of preparing methyl phenacetin which comprises mixing with an inert liquid vehicle a quantity of phenacetin less than a given amount which is to be methylated but sufficient to give a liquid mixture dense enough to float metallic sodium, subjecting the mixture to the action of metallic sodium in quantity less than is molecularly equivalent to the phenacetin present, treating the resultant mass with a methylating agent, adding the remainder of said given amount of phenacetin, repeating the successive treatments with metallic sodium and methylating agent, and separating methyl phenacetin from the reaction mixture.

In testimony whereof I hereunto affix my signature.

EUGENE THEIMER.
